WAND

John W. Petrie, New Haven, Conn., assignor to
Petrie-Lewis Manufacturing Co., Inc., New
Haven, Conn., a corporation of Connecticut

Application April 10, 1945, Serial No. 587,640

6 Claims. (Cl. 287—126)

1

The invention relates to improvements in wands and more particularly to an improved structure of wands having a light-in-weight hollow handle portion and a comparatively heavy tip or end.

Whereas the present invention is particularly applicable to hollow wands of the type generally used by magicians, certain novel features thereof are adapted to be incorporated in the structure of tubular canes, jointed rods, and the like.

In hollow wands of the form used by magicians it is desirable that a solid tip, or end, be rapidly and readily removable and as rapidly and readily applied to, and firmly secured to, the handle portion. It is likewise desirable to releasably but firmly attach a handle to a tubular cane, or to releasably join together the portions of a jointed rod or pointer. One object of this invention is to provide novel means to releasably and tightly join together a handle, or a tip portion, to a hollow cane, pointer, or to a handle portion, respectively.

Another object is to provide a wand, cane, or pointer, composed of two sections which are of such structure that by rotation of one section relatively to the other they will become releasably and tightly joined together.

Still another object is to provide means to tightly, but releasably, join together a cylindrical handle, or tip, to a hollow cylindrical member constructed by rolling a strip of paper or like material into a tube.

A further object is to provide an improved wand, or the like, which will be relatively inexpensive to manufacture, simple in construction, practical, pleasing in appearance, and very efficient and durable in use.

With these and other objects in view, which will appear as the description proceeds, there have been illustrated in the accompanying drawings three forms in which the features and principles of this invention may be embodied in practice.

In the drawing:

Figure 1 is a side view of a wand embodying the features and principles of this invention;

Figure 2 is an enlarged longitudinal sectional view of the jointure between one section of the wand and another section thereof;

Figure 3 is an enlarged cross-sectional view taken on the line 3—3 of Figure 2;

Figure 4 is a longitudinal sectional view of a somewhat modified form of wand or like article;

Figure 5 is a cross-sectional view taken on the line 5—5 of Figure 4;

Figure 6 is a longitudinal sectional view of an-

2

other modified form of wand or like article; and Figure 7 is a cross-sectional view taken on the line 7—7 of Figure 6.

Referring now to the drawing wherein like reference numerals designate like parts throughout the several views, the numeral 11 denotes a hollow section constructed by wrapping a sheet, or strip, of thin material such as paper, or the like, into a hollow tube, or cylinder. The outer layers 12 of the sheet of material forming the tube are secured together by paste, or glue to stiffen it, and the outer surface may be covered with a coating of paint, or other like material, to color the same. The inner layers 13 of the material forming the tube are left loose for a purpose to be hereinafter described.

In the case of a wand a cylindrical tip 14 is attached to one end of the hollow section 11 while in the case of a cane the portion 14 would be the handle while the hollow section 11 would be the cane body. Obviously in the case of a jointed rod the tip portion 14 would be one of the sections while the portion 11 would be another. The wand tip 14 illustrated in the drawing comprises a cylindrical member 15 having a cap 16 covering its inner end portion 17 and with its outer end portion 18 adapted to freely enter one end of the tubular section 11. A relatively shallow slot 19 is provided in the end portion 18 of the member 15 extending diametrically across the end face thereof. A short length of loosely twisted string 20, preferably cotton, is tightly compressed into the slot 19 with its ends 22 and 23 extending substantially equally at each side of the end portion 18 of the member 15 and lying between the inner layers 13 of the tube 11 and this portion 18, when said portion 18 is inserted into said tube 11.

A relative rotation of the member 15 and the tube 11, when the portion 18 of the former is in the latter, will cause the inner layers 13 of the tube 11 to be tightly wrapped upon the portion 18 to releasably secure the tube 11 to the tip 14.

By making the string ends 22 and 23 substantially as long as the length of the portion 18 only a slight relative rotation is required, approximately one-quarter of a turn. A reverse rotation will unwrap the layers 13 from the portion 18 whereby the tip 14 may be drawn away from the tube 11 to withdraw the portion 18 therefrom.

The string 20, due to its action on the layers 13 of the material constituting the tube 11, may be termed a friction imposing means as it frictionally engages the innermost layer 13 to wrap it tightly upon the tip portion 18 to firmly lock

the tip 14 to the tube 11. In the form shown in Figures 4 and 5 the friction imposing means is constituted by a plug 24 of resilient material such as rubber or like material. The plug 24 extends through a hole 25 provided in the end portion 26 of a wand tip, cane handle, or section of a jointed rod and frictionally engages the innermost layer 13 of the material of the tube 11. In the form shown in Figures 6 and 7 the friction imposing means is constituted by a strip 27 of felt, rubber, fabric, or like materials. The strip 27 is preferably seated in a groove 28 provided in the portion 18 for this purpose. Preferably the groove 28 extends lengthwise of the portion 18. If desirable a strip 27 may be applied directly upon the surface of the portion 18 and likewise two strips 27 may be used diametrically opposite as shown in Figure 7.

It will be understood that the novel features and principles of this invention may be embodied in other specific forms without departing from the spirit and essential attributes thereof, and it is therefore desired that the present embodiments be considered in all respects as illustrative and not restrictive, reference being had to the claims rather than to the foregoing description to indicate the scope of this invention.

Having thus fully disclosed the invention, what is claimed as new and for which it is desired to secure Letters Patent, is:

1. In an article of manufacture, the combination of a tubular member constructed by tightly rolling a sheet of material into a tube, the outer layers being bound together by an adhesive and the inner layers being left loose as rolled, a cylindrical member having an end thereof adapted to be inserted into an end of said tubular member, and friction imposing means between said members connected to one and adapted to frictionally engage the other to tightly wrap the inner layers of the material constituting the tubular member onto the cylindrical member when one of the members is rotated relatively to the other.

2. In an article of manufacture, the combination of a tubular member constructed by tightly rolling a sheet of material into a tube, the outer layers being bound together by an adhesive and the inner layers being left loose as rolled, a cylindrical member having an end adapted to be inserted into an end of said tubular member, and friction imposing means secured to the cylindrical member and disposed to frictionally engage the inner layer of the material constituting the

5

tubular member to tightly wrap said inner layer upon the cylindrical member and secure the members together, when one member is rotated relatively to the other.

3. In an article of manufacture, the combination of a tubular member constructed by tightly rolling a sheet of material into a tube, the outer layers being bound together by an adhesive and the inner layers being left loose as rolled, a cylindrical member having an end adapted to be inserted into an end of said tubular member, and friction imposing means secured to the cylindrical member and in frictional engagement with the inner layer of the material constituting the tubular member to separate said loose inner layers from their tightly rolled condition with the outer layers and tightly wrap them onto the cylindrical member to secure the members together when one member is rotated in one direction relatively to the other and to unwrap the inner layers from said cylindrical member to release one member from the other when one member is rotated relatively to the other in the other direction.

4. An article of manufacture in accordance with claim 1, and wherein the friction imposing means is constituted by a short length of string secured to the cylindrical member and extending there-along between it and the inner layer of the material constituting the tubular member.

5. An article of manufacture in accordance with claim 1, and wherein the friction imposing means is constituted by a strip of material secured to the surface of said cylindrical member between it and the inner layer of the material constituting the tubular member.

6. An article of manufacture comprising the combination of a tubular member having its interior composed of wound unconnected layers of material, a cylindrical member adapted to be inserted into said tubular member, and friction imposing means to releasably connect said members together, said means being disposed between and in engagement with the periphery of said cylindrical member and the inner layer of material of the tubular member to tightly wrap the unconnected layers of material of the tubular member onto the cylindrical member when one member is rotated relatively to the other in one direction and to release the layers of material from the cylindrical member when one member is rotated relatively to the other in an opposite direction.
